PULVERIZING MILL

Stanley Johnson, Stockport, England

Application December 11, 1941, Serial No. 422,489
In Great Britain January 27, 1941

5 Claims. (Cl. 83—11)

This invention relates to pulverizing apparatus for the reduction of friable materials to a fine impalpable state by impact. One application of the invention is to the formation of soap powders, but the invention is equally applicable to other uses where pulverization by impact is possible, and includes the pulverization of harder types of material, such as resin, glass and the like.

Pulverizing mills as heretofore known for the production of fine powders, and comprising a series of beaters rotating within a sieve, have been characterized by a small area of sieve surface relatively to the number and speed of the beaters, and have been so formed that the whole of the pulverized material has had to pass through the sieve in order to leave the mill. This has resulted in the clogging of the sieve, necessitating frequent cleaning; and in the consequent obstruction of the beaters requiring more power to drive them, as well as causing undesirable heating of the apparatus. Some materials, such as the soap powders above mentioned, tend to become united under the "thrashing" action of the beaters when the sieves are choked, and may become rock-like, requiring to be chipped from the sieves.

The object of the present invention is to provide improved pulverizing mills of the centrifugal type (i. e. having rotating beaters within a sieve) which eliminate the above-mentioned disadvantages.

According to this invention, a pulverizing mill comprises a relatively large, vertically-disposed, open-ended cylindrical sieve or screen, a series of beaters co-axially mounted within the sieve or screen, at different points in its length, for simultaneous rotation, means for rotating such beaters at high speed, and means for directing the unpulverized material into the open upper end of the screen. Usually, the sieve will be housed within an enclosing wall or chamber, and so as to leave an enclosed cavity around its outer surface to receive the material which passes through the screen, and a hopper will be provided at the upper end of the mill for receiving the unpulverized material and for directing it to the centre of the space in which the beaters rotate.

In preferred embodiments of the invention, the axle or shaft which carries the beaters is supported in a removable footstep bearing, and is detachably coupled to the driving shaft of a motor or other source of power, mounted at the upper end of the mill, so that by removing such

bearing and by uncoupling the shafts, the beater assembly may be removed as a whole for cleaning and/or adjustment purposes, the number, size and position of the beaters being variable as may be desired. Further, the sieve or screen will itself be removably mounted in its enclosing housing, so as to facilitate cleaning and also to allow of the substitution of others of different grade or fineness according to the work to be done.

The material may be fed to the hopper by hand, say by means of a scoop, or automatic means may be provided to feed a constant regular supply of the material to the hopper. Suitable collecting means will be furnished at the foot of the sieve, to collect and direct the pulverized material which has passed through the sieve as well as that which has passed out of the open lower end of the sieve. If and when there is any appreciable difference in the degrees of fineness of these two portions of the pulverized material, means may be provided for isolating them from each other so that the coarser material may be re-fed, or be returned to the hopper of the mill, or may be reserved for special uses where a coarser grade will suit.

In the accompanying drawing:

Fig. 1 is a part-sectional front elevation of a pulverizing mill characterized as one example of the invention;

Fig. 2 is a sectional plan taken on the line 2—2 of Fig. 1;

Fig. 3 is a sectional perspective view of a part shown in Fig. 2;

Fig. 4 is an enlarged view of one of the beaters appearing in Fig. 1, and showing its association with the screen; whilst Fig. 5 is a sectional plan taken on the line 5—5 of Fig. 1.

The example illustrated has been designed and tested for use mainly in pulverizing a sulphonated compound for use as a soap powder. It comprises at the lower part a box or cupboard to receive the pulverized material, and at the upper part a beating chamber mounted thereon, this being open at the top and provided with a hopper to receive the material which is to be milled.

The said base is made up of the box or chamber 1, having a removable side door 2, held in position by the pairs of pivoted latches 3. The door will be as close a fit as possible in its recess, and will have a felt or like packing to prevent escape of dust. Mounted on the top of the box 1, by means of the lugs 4^a, is a cylindrical chamber 4, to the upper end of which is secured the bridge 5, carrying an electric motor 6. The shaft

1 of the motor extends downwardly through the bridge 5 and terminates in a coupling 8.

Arranged co-axially within the chamber 4 is an open-ended cylindrical wire mesh screen 9 of woven steel wire, each end of the screen being fitted with a rubber or like resilient packing member 10. At its lower end the screen 9 rests on a cross-shaped frame 11, being positioned thereon by the lugs 12, whilst at its upper end the screen fits below a hopper 13 having the downwardly-projecting flange 14. The hopper 13 is made in two parts, as is seen more particularly in Fig. 2, so as to be more easily removable, and is secured to the upper end of the outer cylinder 4, a felt packing being provided at the joint to exclude dust.

At the centre of the cross-shaped frame 11, is a ball-bearing footstep 15, which receives the lower end of the beater shaft 16, whose upper end is held in the coupling 8 on the motor shaft 1. This beater shaft 16 is on the axis of the screen 9 and carries a number of beater arms 17, which are spaced equally along the shaft and are also spaced equally around the shaft (see Fig. 5). Each beater comprises a pair of flat metal members shaped at their inner ends to embrace the shaft, and the two members being clamped to the shaft by suitable bolts and nuts or the like. The beaters extend to within a short distance of the screen, but do not touch it.

In order to prevent the inserted material flying back through the feed opening in the hopper 13, a cone-shaped guard 18 is fitted to the beater shaft 16 just below that opening. Moreover, one or more of the beaters may be slightly twisted to create an axial draught, and the box 1 will be fitted with the dilatable bag 19 to allow escape of air whilst retaining any dust caught in the air stream.

As shown in Fig. 1, the lower end of the screen may be fitted with a removable bag 20 to catch any material not passing through the screen, but this will not always be necessary. By increasing, the length of the sieve, and adding to the number of beaters, the uniform pulverizing of the material may in most cases be ensured, but where these changes are not convenient, the material caught by the bag 20 may be fed through the mill a second time, or may be kept separate from the remaining finer material, for use for other purposes.

The beaters and the screen may be plated with chromium or similar hard non-corrosive material, but it will be found that even when not plated, the machine can be run for prolonged periods without becoming clogged. However, it will be seen from the drawing that cleaning of the machine, when required, may be effected very easily; for by removing the securing bolts for the cross-shaped frame 11, that frame may be dropped out of position, and when the coupling 8 is loosened, the beater shaft and beaters may be dropped for cleaning purposes, as also may the screen 9. Similarly, the replacing of a screen by one of different mesh may be carried out quickly and easily.

The rubber or other resilient packing at the ends of the screen 9 eliminates audible rattle whilst the mill is working, but allows a slight vibration of the screen which assists in keeping it unclogged.

The following particulars of size etc. have been found satisfactory in use, and are quoted merely

as being representative of many variations, according to the substance to be dealt with:

Length of screen	inches	32
Diameter of screen	do	12
Mesh of screen	do	1 $\frac{1}{2}$ - $\frac{1}{6}$
Diameter of outer casing	do	20
Number of beaters	do	7-10
Horse power of motor	do	2 $\frac{1}{2}$ -3 $\frac{1}{2}$
Speed of motor	R. P. M.	3,000
Capacity of mill	From 8 cwt. per hour	

Owing to the relatively greater screen capacity, and to the lower end of the sieve being open, clogging does not occur, even with gummy substances such as are used in the manufacture of soap powders, and a constant feed is possible. Moreover, as little or no dust is emitted from the mill, there being no "thrashing" of obstructed material, the mill may be operated in an open room without discomfort.

20 In an alternative arrangement, not illustrated, the box 1 could be dispensed with, at least as a receiving chamber, and the sifted material be allowed to collect in the cylindrical chamber 4, such chamber being enlarged for that purpose. 25 In such case, the material not passing through the screen would be allowed to fall into a suitable receiver below the screen, so as not to foul the rotating beaters.

When the powders to be produced are of a very fine degree, as for example with talcum powder, a silk screen or other suitable textile membrane may be placed around the wire mesh screen 9, or may be sandwiched between two screens, or in some cases may take the place of the screen.

35 Again, when the materials to be pulverized are of a coarse hard nature, as in the case of maize, other provender materials, the effect of the beaters may be enhanced by their being serrated or ribbed, or made with pointed protuberances on their striking faces.

In order further to facilitate the removal of the screen 9, for cleaning or replacement purposes to give access to the beaters, the outer casing 4 may be provided with one or more doors 45 or like removable parts, or may consist of removable panels secured to a fixed frame or skeleton. In all such cases, suitable dust-proof packings will be provided if required.

What I claim is:

50 1. A pulverizing mill comprising an enclosing outer wall, a hopper on the upper end of such wall, a removable frame across the lower end of the enclosure, a cylindrical sieve or screen within the enclosure clamped against the hopper by 55 the frame, a shaft supported by its lower end on the frame and carrying a series of longitudinally- and angularly-spaced beater arms extending to within a short distance of the screen, and means detachably coupled to the upper end of 60 the shaft for rotating it at high speed; the shaft, beaters and screen all being removable from the enclosure by merely removing the said frame and detaching the coupled driving means.

2. A pulverizing mill comprising a cylindrical 65 imperforate open-ended wall, a hopper mounted in the top end of such wall, a frame removably mounted in the lower end of such wall, a substantially cylindrical perforated sieve or screen sandwiched between the frame and hopper, 70 within the wall, a footstep bearing on the frame, an electric motor mounted above the hopper, a shaft supported in the footstep passing through the hopper, and detachably coupled to the motor, a series of beaters secured along and around the shaft with their extremities near but not touch-

ing the sieve and a box-like base as a support, such base communicating with the space between the imperforate wall and the sieve; and having a removable bag on the lower end of the sieve and of the same shape at its mouth as the base of the sieve to isolate unsieved matter falling through such lower end.

3. In a pulverizing mill a cross-shaped frame at the bottom of the mill with thrust bearing at its centre and an upstanding lug at the end of each arm; a hopper of inverted cone shape at the top of the mill with depending lugs thereon; a single perforated cylindrical screen between the frame and the hopper and positioned co-axially with the bearing by such upstanding and depending lugs; resilient packings between the several lugs and the screen; means connecting the frame to the hopper to hold the screen captive between the frame and hopper and a support for such connecting means to hold the assembly 20

4. In a pulverizing mill, an assembly according to claim 3, wherein the connecting means comprises an enclosing wall, a bridge member across such wall above the hopper, a bearing in the bridge member co-axial with the thrust bearing of the frame, a beater shaft journalled in the said bearings, and an electric motor mounted on the bridge member for driving the shaft, and a detachable coupling for drivingly connecting the motor to the shaft.

5. In a pulverizing mill an assembly according to claim 3 wherein the connecting means is secured to the support independently of the securing of the frame to the connecting means and wherein the support has an aperture below the connecting means through which the frame and screen may be withdrawn whilst the connecting means remains in position.

STANLEY JOHNSON.
